UNITED STATES PATENT OFFICE.

GEORGE B. JUSTICE, OF RALEIGH, NORTH CAROLINA.

PARCEL-POST WEIGHING-SCALE.

1,135,812.

Specification of Letters Patent. Patented Apr. 13, 1915.

Application filed July 10, 1914. Serial No. 850,205.

To all whom it may concern:

Be it known that I, GEORGE B. JUSTICE, a citizen of the United States, and a resident of Raleigh, in the county of Wake and State of North Carolina, have made an Improved Parcel-Post Weighing-Scale, of which the following is a specification.

My invention is an improvement in weighing balance scales of a known type.

The improvement is embodied, first, in an attachment for the scale-pan or package-support, consisting in the provision of a shiftable map and a guard superimposed thereon and marked with zone lines. The guard is preferably in the nature of a transparent plate on which concentric circles are inscribed indicating different zones. By shifting the map, any particular town or unit of area may be brought to the center 20 of the pan and the guard, and thus the scale may be conveniently made to apply to any particular town or unit of area.

The details of construction, arrangement, and operation of the device are as herein-25 after described and illustrated in the accompanying drawing in which—

Figure 1 is a side view of the scale as a whole. Fig. 2 is an enlarged side view of the scale beam. Fig. 3 is an enlarged section on the line 3—3 of Fig. 1. Fig. 4 is an enlarged plan view of the pan or platform provided with the map of the United States, and a transparent plate covering the same and inscribed with concentric circles 30 indicating parcel-post zones. Fig. 5 is an enlarged face view of the smaller weight or poise. Fig. 6 is an enlarged transverse section on the line 6—6 of Fig. 4.

In Fig. 1, the pan or platform A is supported upon the shorter arm of a beam B, which is pivoted at b in the usual way, the latter being supported by a hollow post C having an enlarged base D. The pan A is flat and upon it is supported a map of the United 45 States, the same being indicated by E in Fig. 6. Upon the map is placed a celluloid or other transparent plate F, the same being inscribed in concentric circles indicating the different parcel-post zones from one to eight, 50 inclusive. The concentric center of the several zones is indicated at f on the transparent plate F, (see Fig. 4). In this instance the map E is shown adjusted with the city of Lincoln, Nebraska, located at the center, that is to say, coincident with the central opening f in the transparent plate F.

The concentric lines indicating zones radiating from the central point f indicate the zone divisions in a way which is well understood. It will be seen that this map is 60 adapted for use at any locality in the United States; that is to say, at any point which is a unit of area.

The map E and the transparent plate are detachably secured upon the base of the pan or platform A by means of a circular flanged rim G which embraces the edge of the pan and is secured by screws g, as indicated in Figs. 4 and 6. Thus, as shown, the map is held in this instance duly adjusted for the 70 city of Lincoln as a unit of area, or the central point of the zone divisions. But if it is desired to shift the map for another unit of area coincident with the central opening F in the guard plate, the screws G being 75 removed, the flanged rim G may be easily detached, thus permitting the map to be shifted in any direction as required. Thus it may be shifted to the left to allow the city 80 of Washington to be placed in coincidence with the opening f in the guard plate; and in such case of course the left hand portion of the map would project beyond the guard or pan and would be cut off before or after reattachment of the flange rim G. 85

The beam B has two longitudinal divisions separated by a longitudinal slot b'. The upper and larger section is divided by longitudinal transverse lines into squares or rectangles in each of which is a number 90 inscribed. In the upper longitudinal row of these squares the several numerals progress from one upward, and indicate pounds, while the succeeding rows contain numerals indicating prices per pound for different 95 zones.

Under the numeral 1 in the pounds row may be seen the numeral 5, which is the price per pound for parcel post delivery at any point within the first or second zone. 100 Thus the numeral 5 in the second row, which is directly under the numeral 1 in the first row, indicates that the price for shipping one pound in zones 1 and 2 is five (5) cents, while the numeral 6 in the next 105 row below indicates that the price for shipment of one pound to any point in the third zone is six (6) cents, etc., it being seven (7) cents for the fourth zone, eight (8) cents for the fifth, nine (9) cents for the sixth, ten (10) cents for the seventh, and twelve (12) cents for the eighth zone.

The sliding weight or poise H' has a central vertical slot h in its face through which all the numerals which appear in any vertical row on the main section of the scale beam are visible. On each side of the slot h, the weight H is beveled, thus forming opposite faces upon which are inscribed the words "Pounds, Zone, and Cents" for convenience in reading the scale.

10 As indicated in Fig. 1, it is to be understood that a package weighing eight pounds is balanced on the scale-pan, since the weight H is adjusted so that the numeral 8 appears in the pounds row through the slot h. It is, therefore, to be understood that, for the first zone, the postage for the eight-pound package is nine (9) cents, for the second zone it is ten (10) cents, and for the third it is twenty (20) cents, and so on.

15 20 Similarly, any other package whose weight is within the prescribed limit be placed on the pan A and the weight H adjusted along the beam where it balances the package, the number of pounds and the postage for any 25 zone may be read through the slot in the face. The similar weight or poise H' which slides on the lower, narrower, inscribed section of the beam, as shown in Fig. 1, is provided with a slot like the larger weight H and its face is inscribed with the words "Ounces, Letters, Newspapers, and Cents" as shown in Fig. 5. Thus through the slot in the smaller weight H' may be read the weight in ounces and the amount of postage required for letters and the amount of postage required for newspapers. This portion 35 of the invention, to wit, the provision of the lower section of the scale B and the sliding weight thereon is a great convenience for 40 weighing letters and newspapers and thus adapts the parcel post scale for performing an important additional function.

The use of the two weights H and H' also permits weighing in pounds and ounces, as for instance, twelve (12) pounds and four (4) ounces.

The construction of the scale permits the correction of zone distances and rates in case of ruling of Postoffice Department by substituting a new transparent plate or guard 50 for the old one and a new beam for the old one thereby effecting an important economy in that it prevents losses attendant upon the purchase and use of other scales which have been made for a similar purpose and which 55 may be rendered practically worthless by any changes in Government rules. The great advantage of the scale is the saving in time by reason of the map being adjustable to any unit of area so that it is unnecessary for the operator to inspect any other map or make any reference to any list or rate sheet.

In the blank space shown on the scale B which extends beyond the twenty pound 65 limit in all zones after the first, there will be inscribed the rules commonly applying to the parcel post system, together with instructions for the use of the scale.

I claim:—

In a weighing scale of the type indicated, a pan or package-support having a shiftable map of the United States supported thereon, and a transparent guard plate superimposed, and inscribed with concentric circles indicating parcel-post zones, and a flanged rim applied to and upon the edges of the pan, the map, and the guard plate, and detachably secured to the pan, as described.

GEORGE B. JUSTICE.
